UNITED STATES PATENT OFFICE.

ALVAH L. POWELL, OF MILES CITY, MONTANA, ASSIGNOR TO THE A. L. POWELL POWER CO., INC., OF MILES CITY, MONTANA, A BODY CORPORATE.

INTERNAL-COMBUSTION ENGINE.

Application filed February 2, 1921. Serial No. 441,970.

To all whom it may concern:

Be it known that ALVAH L. POWELL, a citizen of the United States, residing at Miles City, in the county of Custer and State of Montana, has invented certain new and useful Improvements in Internal-Combustion Engines, of which the following is a specification.

My invention relates to improvements in internal combustion engines in which I employ a novel means of introducing the charge in the cylinder, and fire the compressed mixture by a method that makes an engine equipped with my improvement more self-contained than another. I am also able to more positively proportion the fuel elements securing, thereby, greater combustion efficiency. In the accompanying drawings I show a form of my improvement, in which—

Fig. 1 is a sectional elevation of the fuel and power pistons, with essential related parts.

Fig. 2 is a sectional elevation of an engine that includes my improvement.

Fig. 3 is a plan, showing arrangement of combustion, air and gas cylinders.

Figs. 4, 5, are diagrams of the operation through a cycle.

Figs. 6, 7, are sectional elevations of engine, the parts being shown at different points of stroke.

Fig. 8 is an elevation of the fuel piston, the lug on head being broken off.

Fig. 9 is a section on *a—b*.

Fig. 10 is a section on *c—d*.

In Fig. 1, a cylinder, A, water jacketed at A^1 , A^2 , in which a power piston A^2 is slidably mounted. In the upper part of A is a second piston, A^3 , having a diameter

preferably smaller than that of A^2 . Piston A^2 carries a wrist pin A^4 on which is hung a connecting rod, A^5 , fitted to a crank, A^6 , of engine shaft, C^7 , by a wrist pin, A^7 . On the upper side of cylinder A are lugs, A^8 , Fig. 2. Only one of these appears in the given view. Through these lugs a pin, A^9 , supports a pivoted lever, B. Similar lugs, B^1 , on secondary piston A^3 carry a pin, B^2 , that engages a groove in end of lever

B, Fig. 2. From the other end of B a crank rod, B^3 , supported by a pin, B^4 , Fig. 1. Cam rod B^3 is supported, in its vertical movement, by a drilled lug, B^5 . On lower end of said cam rod a roller, B^6 , Fig. 2, en-

gages a groove in a positive cam, B^7 . The engine may be one of one or more cylinders, but in this application multiple cylinders are assumed, as shown in plan, Fig. 3. It will be noted that at the right hand end are two independent cylinders. These are, respectively, B^8 , B^9 . Cylinder B^8 is for compressing air. In it moves a piston, C, from which a connecting rod, C^1 , connects it to a crank, C^2 , on a shaft, C^3 , (Fig. 2). Wrist pins C^4 , C^5 , are of the conventional form, providing for the oscillation of rod C^1 . Cylinder B^9 has piston, wrist pin, and connecting rod similar to those in cylinder B^8 and connected to a crank on shaft C^6 , (dotted lines, Fig. 2) by the same means used with the other cranks. The power shaft C^7 is on a line parallel with shafts C^3 , C^6 , and the three are joined by the large diameter gear, C^8 , that meshes with the pinions C^9 , C^{10} , (pinion C^{10} is shown in dotted lines, Fig. 2). Only one operating cam, B^7 , is shown, Figs. 2, 6, 7. This cam is preferably keyed to a shaft D on which is a gear, D^1 , (dotted lines, Figs. 2, 6, 7), that meshes with a pinion, D^2 , on power shaft C^7 .

The pistons in cylinders B^8 , B^9 , make two strokes to one of the power piston A^2 , and the cam shaft D makes one revolution to two of the power shaft.

From air cylinder B^8 a pipe passes along the upper side of power cylinders (Fig. 3) and connects with each of them by means of branches, D^3 . On the opposite side similar connection is made between power and fuel cylinder B^9 , by the pipe D^4 , and branches, Fig. 3. Check valves D^5 , D^6 , Figs. 1, 2, 3, are placed in the branches for purposes to be described.

The operation of the engine is as follows:

On outstroke of piston A^2 it is followed by the secondary piston A^3 . Piston A^3 is divided into annular chambers E, E^1 , each of which connects with a series of holes in the circumference of A^3 , Figs. 1, 8. In Fig. 9 a section on *a—b*, Fig. 8, is given, the related piston chambers E, E^1 , being shown; while in Fig. 10, the circumferential holes are shown on section *c—d*, Fig. 8. As pistons A^2 , A^3 advance the row of holes designated E^2 , Fig. 8, uncovers and an explosive charge carried in annular chamber E^1 exhausts into space between piston A^2 , piston A^3 , and head of cylinder A.

The expression "exhaust" is here intended to indicate an equalization of pressures between the said cylinder space and that within the said annular space. The second row 5 of holes, E^3 , next uncovers, liberating a charge of air previously compressed to ignition temperature. The power charge is fired by this, and piston A^2 continues on, the balance of its stroke developing power. 10 Piston A^3 , moved by cam B^7 , remains stationary until return of A^2 . During this stroke operable exhaust valve E^4 opens and the burned charge passes out by said valve. At latter part of clearance stroke cam B^7 15 returns piston A^3 to the original position shown in Fig. 1. On suction outstroke inlet valve E^5 opens, admitting a charge of air. On succeeding clearance stroke this air is driven out through valve E^4 which 20 had closed on suction end and re-opened on return of piston A^2 . The indrawn and exhausted air not only makes scavenging more thorough, but aids in cooling cylinder and piston. 25 The annular chamber, E^1 , is charged from pipe line D^5 , that runs to cylinder B^9 . In this cylinder air and fuel are drawn from a carburetor, or other source, not shown, through check valve E^6 , Figs. 6, 7. The 30 piston in said cylinder compresses the mixed charge into pipe line D^5 , through check valve D^3 , Fig. 2, from which it enters the annular piston chamber E^1 , by the port shown in Fig. 1, at E^8 . During the 35 movement of piston A^3 it acts as a piston valve, closing port E^8 as it descends. The air compression is effected in cylinder B^8 . The action is exactly the same as that already described for cylinder B^9 . Air 40 is taken in from atmosphere through a check valve, H . The highly compressed air passing into annular chamber E ,

through a check valve, D^4 . Each cylinder is provided with check valves, as shown in Fig. 3.

I also provide cooling means for piston A^3 . Flexible tubes, G , G^1 , communicate with said piston and a supply source of water, preferably. Circulation passes in by tube G and out by G^1 . Water spaces 50 are cored in said piston and shown, in section, at G^2 , G^3 , Fig. 1.

In diagrams, Figs. 4 and 5, the detail order of operation may be followed. Ignition occurs at a point x , Fig. 5, and the impulse is through the arc $x-y$. The piston A^3 moves upward on the arc $l-m$, and down on the arc $m-x$. In Fig. 4, the detail operation of piston A^3 is shown, according to its cycle.

I thus obtain an engine relatively simple, self-igniting, and, positively charged from a self-contained source operating within the structure itself.

What I believe is new and ask to have 65 protected by Letters Patent, is

In an internal combustion engine, a power piston, a secondary piston, annular spaces in said secondary piston, holes from the said annular spaces to the circumferential 70 face of said secondary piston, means for charging one of said annular spaces with a fuel charge, means for charging another annular space in said secondary piston with air compressed to ignition temperature, cylinders within which said pistons operate, intake and outlet valves, operable means for said outlet valve, a power shaft, and means for rotating said power shaft by the movement of said power piston, substantially as 75 described.

In testimony whereof I affix my signature.

ALVAH L. POWELL.
